HYDROPLANE GLIDER

Igor B. Bensen, Raleigh, N.C., assignor to Bensen Aircraft Corporation, Raleigh, N.C., a corporation of North Carolina

Application February 25, 1959, Serial No. 54,742

Term of patent 14 years

(Cl. D71—1)

FIG. 1

FIG. 2

FIG. 3

Figure 1 is a perspective view of a hydroplane glider embodying my new design and illustrating the hydroplane glider in flight condition;

Figure 2 is a front elevational view of the hydroplane glider; and

Figure 3 is a rear elevational view of the hydroplane glider.

What I claim is:

The ornamental design for a hydroplane glider, as shown.
